BOTTLE LOCK

Lester P. Barlow, Stamford, Conn.

Application August 8, 1934, Serial No. 738,953

4 Claims. (Cl. 215—32)

This invention relates to a bottle adapted especially for the marketing of wine, whiskey and other spirituous liquors. It is usable also for the protection of the sale of other commodities of 5 value.

Due to the activity of bootleggers in manufacturing counterfeit bottles, and in utilizing old bottles for refilling purposes, and in draining the contents from bottles containing fine liquors 10 and substituting therefor cheap liquors, both the Government of the United States and various private parties have for a considerable period been attempting to obtain a bottle which will foil such operations. It is the purpose of my invention 15 to devise a bottle which, while being refillable, is what I term non-repackeable, and to devise a sealing arrangement for the bottle which will be difficult to counterfeit. In other words, in my invention, not only is the seal difficult to 20 make, but once the bottle is acted upon in a definite manner, it cannot be refilled or repackaged and sold to the public under the guise of being a newly packaged bottle.

My invention is more particularly related to 25 the disclosure of my application, Serial No. 735,560 filed July 17, 1934, and forms a modification of the invention disclosed therein.

In both my first application and in this application, I disclose a bottle in which the upper portion of the neck is readily removable at will, thus 30 destroying the original bottle in so far as its general makeup is concerned, while preserving it for use as a container of the opened or unsealed liquor. I realize that the art of bottles with removable necks or readily severable necks is highly 35 developed, but I believe that my improvement is entirely novel and forms a worth while contribution to the prior art.

I utilize a bottle having a rather unique form 40 of severable top which is so constructed that it will be shatter-proof and will not fly into small fragments upon being severed from the main portion of the bottle neck. Also, because of its particular construction the upper half of the neck 45 is readily severable when a hard blow is imparted thereto, thus making it comparatively simple to open the bottle.

My invention comprises also means whereby the 50 particular section of the bottle which is severed will be immediately covered upon severance, so that the rough edges thereof will not remain to injure the person handling the bottle thereafter. The particular construction just referred to acts 55 also to maintain the two portions of the neck in a somewhat assembled relation even when the

neck is broken by a hard blow, so that the severed portion will not fly off to injure anyone.

My invention also comprises the arrangement of means for cushioning the shock and absorbing any movement of the bottle neck at the time that 5 it is broken. The sealing of the bottle is also rather novel and forms part of this invention.

While I have indicated the general features of my invention, I shall now refer to the drawings wherein I show a particular embodiment of my 10 invention. Fig. 1 is a view of the bottle comprising my invention showing it in its sealed condition. Fig. 2 illustrates the upper portion of the bottle severed therefrom. Fig. 3 illustrates the neck of the bottle remaining after the upper portion 15 is removed therefrom. Fig. 4 is a plan view of a seal utilized in my invention. Fig. 5 is a cross section of the neck of the bottle in Fig. 1 showing the parts in their original condition. Fig. 6 shows what happens when the bottle neck 20 is severed in a normal way. Fig. 7 shows what happens as the bottle neck is removed or when it is severed in a rather hard manner. Fig. 8 illustrates a modification of the invention of Figs. 1 to 7. 25

Referring now more particularly to the drawings, reference numeral 10 represents a bottle having a neck 11 which is divided into a lower portion 12 and an upper portion 13 joined by a section 14 of predetermined strength. This section 14 is preferably of less thickness than the remainder of the neck and is also preferably mutilated as by a diamond scratch on its inside and/or outside surface. The upper portion 13 of the neck is covered by a binding material 15 30 which is of the type manufactured by the Du Pont Company and is adapted to bind the glass thereto 35 so as to render it non-shatterable. Naturally, my invention contemplates the use of any other of the possible constructions which may be utilized for shatter proofing the upper portion of the bottle, so that when it is broken as by a 40 hard blow, there will be no fragments flying into space.

A ferrel 16 of annealed glass is secured within 45 the lower and permanent portion 12 of the neck 11 as by a silica cement 17 which has the same characteristics as glass, and cannot be destroyed or removed without the destruction of the glass 50 of the bottle or the plug. This ferrel 16 is adapted to hold therein a cork 18 as is clearly illustrated. A resilient live rubber collar 19 is adapted to encircle the neck 11 as illustrated and to be maintained under tension against the neck 55

so as to act as will be indicated later on in the description.

The bottle is sealed by the utilization of a glass sealing plug 20 which is sealed within the bottle 5 by cement of the type utilized to secure the ferrel 16. This glass plug 20 is preferably engraved or etched so that it will bear the legend shown in Fig. 4. Actually it is intended to be made under government control and to be used as revenue 10 stamps are used today. Since this plug is permanently secured to the upper portion 13 of the neck 11, it can never be removed therefrom and may never be utilized once the bottle is opened.

The action of the construction illustrated in 15 Fig. 5 is best understood by reference to Figs. 6 and 7. In Fig. 6, it is readily seen that when the upper portion 13 of the neck is struck a blow it will immediately sever along its section 14. It will be held in assembled relation to the remainder 20 of the neck by the covering 19 and the shock of the blow will be absorbed by the cork member 18. Should the blow be struck more severely as in Fig. 7, the cork 18 will be called on to absorb even more of the blow. Fig. 7, also illustrates 25 just how the sleeve 19 reacts in immediately covering the severed section 14 of the bottle so as to prevent injury to the user of the bottle. Fig. 3 illustrates just how the sleeve 19 wraps itself over the section 14 to not only cover 30 that section but also to preserve the appearance of the bottle so that it may be used as a container of the liquor. Fig. 2 illustrates the severed portion of the neck which is thrown away.

Fig. 8 illustrates a modification of the invention 35 described in the previous figures. A cork ferrel 25 is utilized and is merely forced into the lower half 12 of the neck 11. Instead of a cork stopper, a hard porcelain stopper 26 is utilized and this stopper is preferably equipped with a 40 resilient shock absorbing member 27, although that is not entirely necessary. When a blow is struck against the upper half 13 of the neck of the bottle, the shock of the blow will be absorbed by the ferrel 25 rather than the stopper member 26. Should the blow be extremely severe, naturally 45 the resilient member 27 will be required to take up much of the blow.

In this modification the shatter proofing material 50 15 extends downwardly so as to cover the entire neck of the bottle. Preferably this material is severed after application along a line 14' opposite the diamond scratch line on the special section 14, and in this way assists in the proper severance of the bottle neck.

In Fig. 8, the neck of the bottle 13 is shown as 55 ground out as at 28 to help in securing the plug member 20 within the neck. Preferably also, the inside of the upper neck portion 13 is tapered downward and the plug member 20 is correspondingly tapered and may be inserted to the proper depth and then sealed by the cement 29 which is of the same character as the cement 17 utilized in the modification of Figs. 5, 6 and 7. Because of the tapering relation of the plug 20 60 and the bottle neck, it is unnecessary to grind both the neck and the plug. It is quite readily

understood that the plug will descend the proper depth and then will be seated in the neck.

From the description indicated, it is readily seen that in my bottle, the rubber member 19 acts as a uniting member for the two halves of 5 the neck when the upper half is severed along its predetermined section 14. It is also readily seen that the rubber member 19 acts to wipe over and cover the severed section 14 so as to protect the user of the bottle against injury. It is 10 also seen that the cork member 18 in the modification of Fig. 6 acts as a shock absorbing member while in Fig. 8, the ferrel 25 itself acts as a shock absorbing member. The sealing of the 15 plug member relatively to the upper half of the neck is substantially similar to that disclosed in my application referred to supra except that herein I contribute the feature of the tapered neck and the tapered plug member.

While I have disclosed a particular modification 20 of the invention, it should be understood that I consider the various features especially emphasized to be of considerable value and to perform a valuable and real contribution to this art. I therefore feel myself entitled to a rather 25 broad monopoly along the lines set forth in the claims appended hereto.

I claim.

1. In a bottle of the class described, a neck arranged to be severed along a predetermined section, the portion of the neck above said section being bound by a shatter proofing covering whereby it may be struck when it is desired to sever the neck, without the attendant danger of 35 flying glass particles, and a covering element maintained in position to slip over the severed section of the remaining neck so as to protect the user of the bottle against injury.

2. In a bottle of the class described, a neck arranged to be severed along a predetermined section, the outside of the neck above said predetermined section being bound by a covering of shatter proofing material whereby said upper neck portion may be struck to sever it from the lower portion of the neck, without the attendant 45 danger of flying glass particles.

3. In a bottle of the class described, a neck arranged to be severed along a predetermined specially prepared section, the outside of the neck above said predetermined section being bound 50 by a covering of shatter proofing material whereby said upper neck portion may be struck to sever it from the lower portion of the neck, without the attendant danger of flying glass particles.

4. In a bottle of the class described, a neck arranged to be severed along a predetermined section, the outside of the neck being bound by a covering of shatter proofing material whereby 60 said neck portion may be struck to sever it along said predetermined section without the attendant danger of flying glass particles, said covering being severed circumferentially opposite said predetermined section so as to assist in the proper severance of the bottle neck.

LESTER P. BARLOW.
